UNITED STATES PATENT OFFICE.

JAMES TEALL, OF ROCHESTER, NEW YORK.

BILL-FILE.

SPECIFICATION forming part of Letters Patent No. 482,659, dated September 13, 1892.

Application filed July 7, 1892. Serial No. 439,214. (No model.)

To all whom it may concern:

Be it known that I, JAMES TEALL, a citizen of the United States of America, residing at Rochester, in the county of Monroe and State 5 of New York, have invented certain new and useful Improvements in Bill-Files; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

This invention relates to improvements in 15 bill or paper files; and it consists in the construction of the movable frame and means employed for actuating the same toward the vertical pins against which said movable frame bears, as will be hereinafter fully set 20 forth, and particularly pointed out in the claims.

In the accompanying drawings, which illustrate my invention, Figure 1 is a perspective view of a bill-file constructed in accordance 25 with my invention, the cap or cover being shown in dotted lines. Fig. 2 is a transverse sectional view, and Fig. 3 is a detail perspective view.

A designates the base, and B the vertical 30 tubular pins which are secured near one end of the base.

C designates a movable frame, the upper ends of which are bent to engage with the vertical pins when swung toward the same.

35 The lower cross-bar c of the movable frame has rigidly secured thereto a concave plate b, against which abuts the central portion of a wire or bar spring D, said spring being bent on each side of its center to form curved portions, the ends being bent around the cross-bar and extended to bear against the covering-plate or casing E. By this construction the wire or bar spring is looped near its ends and the central portion thereof bears upon

45 the concave plate b to one side or beneath the center of the cross-bar c. When the ends of the swinging frame bear against the vertical pins B B, this spring will bear against the concave plate at a point beneath the bar 50 c, and when the frame is swung back against the lugs d, formed on the covering-plate, the spring will bear against the concave plate

near its upper edge. The resiliency of the spring is principally at the curved portions on each side of its center, and the normal 55 tendency of the central curved portion is downward. By means of the particular spring herein shown the swinging frame can be held in both positions, and the device, being simple, is not liable to get out of order. 60

Having thus described my invention, I claim—

1. In a paper-file, a swinging frame having the lower or connecting portion within a cover or casing, said connecting portion having a 65 plate secured thereto which extends beyond each side of the same, and a spring located within the casing and adapted to exert a spring-pressure upon the plate, substantially as shown, and for the purpose set forth. 70

2. A bill or paper file having a swinging frame made up of a single piece, a plate b, secured to the central portion of said swinging frame, and a spring having its terminal members bent to embrace the connecting portion 75 of the swinging frame and bear upon the plate carried thereby, substantially as shown.

3. In a bill-file constructed substantially as shown, a swinging frame C, provided with a concave plate b, and a spring having a central 80 portion which bears upon said plate, the terminal members being curved and looped around the transverse portion of the swinging frame and adapted to contact with a casing or cover, substantially as shown, and for 85 the purpose set forth.

4. In a bill-file, the combination of a base having upwardly-projecting pins B B, a swinging frame made of a single piece, the connecting portion thereof carrying centrally a 90 plate, and a spring adapted to engage with said plate on opposite sides of the connecting portion, so as to hold the swinging frame either in contact with the pins or away from the same by exerting a spring-pressure on opposite sides of the cross-bar, substantially as 95 shown, and for the purpose set forth.

5. In a bill-file, the combination of a base carrying upwardly-projecting pins, a casing retaining therein a swinging frame, said casing having lugs adjacent to the openings through which the connecting-bar of the swinging frame passes, the connecting-bar having a plate secured thereto, a wire or bar 100

spring having a central portion which bears upon the plate, and curved portions connecting the central portion with the terminal members, said terminal members being looped over
5 the connecting-bar of the swinging frame and the ends extended to bear against the casing, substantially as shown.

In testimony whereof I affix my signature in presence of two witnesses.

JAMES TEALL.
